UNITED STATES PATENT OFFICE.

RILEY ESTEL SCOTT, OF PEEKSKILL, NEW YORK.

MEANS FOR DROPPING PROJECTILES FROM AERIAL CRAFTS.

991,378.

Specification of Letters Patent.

Patented May 2, 1911.

Application filed May 4, 1910. Serial No. 559,385.

To all whom it may concern:

Be it known that I, RILEY ESTEL SCOTT, a citizen of the United States, residing at Peekskill, in the county of Westchester and State of New York, have invented certain new and useful Improvements in Means for Dropping Projectiles from Aerial Crafts; and I do hereby declare the following to be a full, clear, and exact description of the invention, such as will enable others skilled in the art to which it appertains to make and use the same.

This invention relates to means for dropping or shooting projectiles carrying explosives from aerial craft, and has for its object to provide an apparatus whereby the operator may place himself in a position directly above the object to be attacked, or if the craft be in motion, to enable the operator to drop or shoot the projectile at a given time before he reaches a vertical position over the target. And in either case to enable the operator, by the means hereinafter described, to strike the object aimed at with more certainty and greater accuracy than has heretofore been possible.

With these objects in view, the invention consists in the novel details of construction and combinations of parts more fully hereinafter disclosed and particularly pointed out in the claims.

Referring to the accompanying drawings forming a part of this specification, in which like numerals refer to like parts in all the views—Figure 1 is a diagrammatic view of a well known form of air craft equipped with my invention, Fig. 2 is an enlarged plan view of the projectile carrying framework, Fig. 3, a sectional view through the center of said framework, and Fig. 4, an enlarged detail view of one of the projectile tubes.

1 indicates any suitable form of air craft, and 2 any suitable platform or support for the operator who is to discharge the projectiles. The motor for the craft proper and the means of propelling the same may be of any well known and approved construction and therefore are not illustrated.

Suitably carried by the craft or balloon 1 is a support or framework 3, in which is preferably mounted a ring 4, provided with gimbals 5, and in this ring 4 is a second ring 6, provided with the gimbals 7 pivoting in the said ring 4. The gimbals 7 are mounted in a line at right angles to the line joining the gimbals 5, and therefore the ar-

rangement as a whole constitutes the well known universal mounting used wherever it is desired to maintain a surface horizontal. Inside the ring 6 are a series of tubes 8, which may be simple tubes, or gun barrels adapted to receive light charges of powder. Inside the tubes 8 fit the projectiles 9, which may be of any suitable form or construction, and which are preferably provided with guide vanes such as 10, in order to keep the projectiles vertical during flight. In order to accomplish this latter purpose, it is desirable to have the center of gravity of the projectiles located near their pointed ends, and also to have the vanes 10 of sufficient length and size to insure a steady downward flight.

Across the tubes 8 are preferably placed supporting bars 12, over which pass sliding rods 13. The upper end of the rod 14, to which the vanes 10 are attached, is cut away as shown at 15, and is provided with a roller 16 under which the end of the rod 13 fits, and thereby supports the projectile 9, as best illustrated in Fig. 4.

Extending over the tubes 8 and at right angles to the bars 12 is a bar 17, pivoted as at 18 to the ring-like support 19 located near the center of the ring 6. The sliding rod 13 also passes over the pivoted bar 17 as illustrated, and slides thereon, as will be disclosed below. The said bar 17 has an abutment 20 near its inner end, and also carries a pin 21 at a short distance from said abutment. The sliding rod 13 normally rests against said pin 21 when it is incapable of being moved from under the supporting roller 16. The said pin 21, however, may be conveniently controlled by a rod 22, curved as at 23, where it passes through the pin 21, and jointed as at 24 where it passes through the hinge 18. A guide lug 25 mounted on a support 19 is also provided for the rod 22, and said rod is preferably provided with an upturned end 26, for a purpose to be described below.

In order to release the projectile 9, I preferably provide a firing pin 30, controlled by a spring 31 abutting against said firing pin 105 and against a lug 32 carried by the bar 12.

When the spring is not under compression, as shown in Fig. 4, the sliding rod 13 is securely held in place as illustrated, and has no tendency to move in any direction. When, however, it is desired to release a projectile 9, the firing pin 30 is moved

outwardly until its lower end 33 enters the recess 34 in the rod 13, whereupon the spring 31 is placed under compression and there is a tendency to move the rod 13 inward 5 and to release the projectile 9. With the spring under compression, as just described, it is evident that if the trigger rod 22, be moved inward its curved portion 23 will force the pin 21 downward, thereby 10 releasing the rod 13 and permitting the same to fly inward against the abutment 20, and to thereupon release the projectile 9. In order that the spring 31 may be kept under compression and the firing pin 30 locked in 15 place, the recess 34 is provided with a notch 35, into which the lip of the projection 33 may enter and thereby prevent the pin from being withdrawn from the notch 35, unless it is moved outwardly before it is moved up- 20 wardly. The firing pin 30 may be moved upwardly by hand, when the firing operation is to take place, but I prefer to provide a spring 36 for automatically accomplishing this movement. The inner end of the sliding 25 rod 13 passes under a guide lug 37, as shown in Fig. 4, in order to steady its movement.

In order that the firing operator may be able to carefully sight the target, the central supporting ring 19 is provided with a 30 tube 40, which is firmly supported in the rings 41 and 42 and is further supported from the tubes 8 by the brackets 43. The tube 40 carries a telescope 45, which may be conveniently provided with cross hairs 35 or spider lines, and the platform 2 is so located and so suspended, as by the means 46, as to enable the operator to keep his eye constantly on the object while viewing the same through said telescope. In order to 40 facilitate the sighting of the projectiles, any suitable means, as a cord 47, may be attached to any fixed portion of the machine, and by means of which the operator may pull himself from one position to another, in order 45 to counteract the varying movements of the craft, and thereby maintain himself in a fixed relation with the eye-piece of the telescope.

Since the projectiles 9 may be of considerable weight, it is desirable to be able 50 to fire the same in pairs so as not to disturb the equilibrium of the craft. In order to accomplish this, the tube 40 may be provided with a ring 48, capable of sliding on said tube, which ring may carry cam surfaces 49, adapted to fit over the bent up projections 26 of the firing or trigger rods 22, and when depressed to force said trigger rods inwardly through the pin 21, so 55 that projectiles on diametrically opposite sides of the telescope will be released simultaneously in pairs. Of course, if for any reasons it may be desired to fire a single projectile at a time, the same may be released by simply pressing upon the up-

turned portion 26 of the rod 22 with the fingers, or else the cam surfaces 49 may be dispensed with, except for the particular projectile which it is desired to fire singly.

In order to conveniently load the projectiles into the tubes 8, the bars 12 and 17 together with the firing pin 30 and sliding rod 13 may be lifted on the hinge 18, as indicated in dotted lines in Fig. 4, whereupon the firing rod 22 will break on its hinge 24, and the whole will thereupon be removed from over the end of the tube and the projectile may be readily put into the proper position.

Of course, the projectiles may be loaded 80 into position through the lower ends of the tubes without moving the parts just mentioned on the hinge 18, but if the hinge is provided the tubes 8 may be rifled so that should the upper ends of the tubes 8 be 85 covered and a charge of powder placed in said tubes, the projectiles will thereupon be forced out of the same and given a rotary motion on their axes through the rifling that may be employed. In most cases, however, the vanes 10 can be relied upon to 90 steady the projectiles.

Of course the telescope may be provided with any suitable and well known adjusting means (not shown), in order to keep it 95 at right angles to the plane of the ring 6, and also to adjust its cross hairs in azimuth so that one of the same may be placed in the line of flight.

When the balloon 1 or other craft is stationary over the object to be attacked, the projectiles may be simply released as above described after the cross hairs of the telescope are located on said object; but when the balloon is in motion the telescope may 100 be set at given angles to the plane of the ring 6 by any well known suitable means, and the projectiles released at the proper 105 instants to cause their trajectories to pass through the target.

Suitable tables could be used to aid in determining the instants of release or the angles the telescope should make with the ring 6 when the projectiles are fired.

It is obvious that those skilled in the art 115 may vary the details of construction and the arrangement of parts without departing from the spirit of my invention, and therefore I do not wish to be limited to such features except as may be required by the 120 claims.

What I claim is:—

1. In an aerial craft, the combination of a support; a pair of rings pivoted at right angles to each other carried by said support; a tube adapted to carry a projectile carried by said rings; means comprising a sliding rod to support said projectile; means for moving said rod; and means for sighting said tube, substantially as described. 130

2. In an aerial craft, the combination of a support; a pair of rings pivoted at right angles to each other carried by said support; a tube adapted to carry a projectile carried by said rings; means comprising a sliding rod to support said projectile; means comprising a pin and a spring for moving said rod; a trigger rod for controlling said sliding rod; and means for sighting said tube, substantially as described.
3. In an aerial craft, the combination of a support; a universal mounting carried by said support; a tube adapted to carry a projectile carried on said mounting; a sliding rod for holding said projectile; a pivoted support for said rod; a sliding pin carried by said support; a trigger rod for controlling said sliding rod; and a telescope

for sighting said tube, substantially as described.

4. In an aerial craft, the combination of a support; a universal mounting comprising a plurality of rings having gimbal pivots carried by said support; a plurality of projectiles carried by said mounting; a sighting means comprising a telescope carried by said mounting; and means comprising a pin, a trigger rod and a cam surface for firing said projectiles simultaneously, substantially as described.

In testimony whereof, I affix my signature, in presence of two witnesses.

RILEY ESTEL SCOTT.
